CLAIM

The ornamental design for an audio mixer, as shown and described.

DESCRIPTION

FIG. 1 is a front isometric view of the audio mixer of the present invention;

FIG. 2 is a top view thereof;

FIG. 3 left-side view thereof;

FIG. 4 is a right-side view thereof;

FIG. 5 is a rear view thereof; and,

FIG. 6 is a front view thereof.

The broken lines showing environmental structure of the audio mixer form no part of the claimed design. The dash-dot rectangle indicates the extent of the surface being claimed. The dash-dot rectangle does not indicate a claimed feature of the structure. The dash-dot rectangle encloses the claimed subject matter.
